INSIDE PIPE CUTTER

James Buckles, Goose Creek, Tex.

Application September 26, 1935, Serial No. 42,171

3 Claims. (Cl. 164—0.8)

This invention relates to an inside pipe cutter.

An object of the invention is to provide a pipe cutter shaped to be inserted into a pipe, stuck in a well bore, and adapted to cut by rotation.

5 Another object of the invention is to provide a pipe cutter comprising a cutter body having outwardly movable blades mounted therein normally held in retracted position in combination with a mandrel movable axially through the body arranged to engage and move the blades outwardly while the device is being rotated in the pipe to be cut.

10 Another object is to provide a cutter of the character described wherein the mandrel is normally held in inactive position by a yieldable spring or seat with means thereon for the application of liquid under pressure thereto to actuate the mandrel into contact with the blades to move the blades outwardly into cutting relation 20 with the pipe to be cut.

15 A further feature resides in the provision of a pipe cutter of the character described wherein the mandrel constitutes also a weight suspended from, and having a swiveling connection with, a wire line whereby the mandrel may be lowered into position to actuate the blades outwardly into pipe-cutting position, or elevated.

25 With the above and other objects in view the invention has particular relation to certain novel 30 features of construction, operation and arrangement of parts, examples of which are given in this specification and illustrated in the accompanying drawings, wherein:

35 Fig. 1 shows a vertical sectional view of the cutter.

Fig. 2 shows a cross-sectional view taken on the line 2—2 of Fig. 1.

Fig. 3 shows a cross-sectional view taken on the line 3—3 of Fig. 1.

40 Fig. 4 shows a vertical sectional view of another form of the cutter, showing the blades in inactive position, and

45 Fig. 5 shows a fragmentary side view, partly in section, of the form of cutter shown in Fig. 4, with the blades in active position.

50 Referring now more particularly to the drawings wherein like numerals of reference designate similar parts in each of the figures, the numeral 1 designates a tubular cutter body adapted to be connected to the lower end of a tubular operating string 2 whereby the cutter may be rotated from the ground surface.

At its lower end the cutter body is provided with the vertically elongated tubular slots 3 in which the cutter blades 4 work. The blades are

pivoted at their upper ends on the cross-pins 5 and their lower ends are provided with the outwardly directed bits 6. The blades are normally held retracted by the flat springs 7 whose upper ends are fastened to the body and whose lower ends press against the outer sides of the blades as shown in Figs. 4 and 5. Any desired number of blades may be employed, three, the preferable number, being shown.

5 Axially movable in the body 1 there is a 10 mandrel 8 and surrounding this mandrel there is a strong coil spring 9 whose lower end is seated on the inside shoulder 10 of the body and whose upper end resists against the nut 11 threaded on the upper end of the mandrel. This nut may be 15 adjusted to regulate the tension on the spring 9.

The upper end of the body is formed with the cylinder 12 and on the upper end of the mandrel, fitting closely within this cylinder, there is a piston 13.

20 The mandrel 8 has an axial channel 14 therethrough from end to end. The inner sides of the blades 4, beneath the pins 5, are provided with the downwardly converging bearing faces 15, and the lower end of the mandrel 8 is tapered 25 to engage said faces and force the lower ends of the blades outwardly upon downward movement of the mandrel.

20 In operation the cutter is lowered into the well bore and into the pipe 16 stuck therein. Liquid 30 under pressure is then forced down through the stem 2 and against the piston 13 and the mandrel 8 will thereby be forced downwardly and will gradually move the blades 4 outwardly, carrying the bits 6 into contact with the pipe to be cut. 35 Meanwhile, sufficient liquid will pass through the channel 14 to flush the bits and to keep them cool during the cutting operation. When the pipe 16 is severed, the liquid pressure may be released and a spring 9 will withdraw the mandrel upwardly allowing the springs 7 to retract the blades and the tool may then be withdrawn from the pipe.

40 In actual practice a spear is usually carried by the operating string 2 so that when the cutting 45 is completed, the cutting tool may be lowered and the spear engaged with the cut-off section and said section removed with the cutter, or the cutter may be withdrawn from the well, and a pipe puller lowered into engagement with the cut-off 50 section, and said section removed preparatory to making another cut.

45 In the form shown in Figs. 4 and 5, the mandrel 8a is in the form of an elongated weight adapted to be let down through the cutter body 55

1a to actuate the blades, as hereinabove explained. This weight, or mandrel 8a, may be let down and withdrawn through the instrumentality of the cable 17 which has a swiveling connection with the upper end of the mandrel 8a as shown in Fig. 4. This swiveling connection is necessary so that during the rotation of the cutter, the cable 17 will not be twisted and injured. In this form there is sufficient clearance between the mandrel 8a and the body 1a to permit liquid to circulate down to the bits for flushing them and keeping them cool.

In other respects the form shown in Fig. 4 is the same as that shown in Fig. 1.

15 The drawings and description disclose what is now considered to be preferred forms of the invention by way of illustration only, while the broad principle of the invention will be defined by the appended claims.

20 What I claim is:

1. A pipe cutter adapted to cut by rotation and comprising a tubular cutter body having an inside shoulder, outwardly movable blades whose upper ends are pivoted to the body and whose lower ends are swingable outwardly and formed with outwardly directed bits, said blades having downwardly converging inside faces, means normally holding the blades retracted into inactive position, a mandrel movable axially in the body 25 having an adjustable stop thereon, a coil spring on the shoulder and acting against the stop and normally holding the mandrel elevated into inactive position, a piston on the mandrel above the stop and fitted in the body, a tubular operating string to the lower end of which the body is attached and through which liquid under pressure may be forced against the piston to move the mandrel downwardly against said faces to force the blades outwardly.

40 2. A pipe cutter adapted to cut by rotation and comprising a tubular body whose upper end is formed into a cylinder, said cylinder having an inside annular shoulder at its lower end, outwardly movable blades whose upper ends are pivoted to the body and whose lower ends are swingable outwardly and formed with outwardly directed bits, the blades having downwardly con-

verging, inside faces, means normally holding the blades retracted into inactive position, a mandrel movable axially in the body and extended into the cylinder, an annular inside shoulder in the body spaced beneath the lower end 5 of the cylinder, a coiled spring resting on said last mentioned shoulder and supporting the mandrel and normally holding it elevated into inactive position, means on the mandrel for regulating the compression of said spring, a piston 10 on the mandrel fitted within the cylinder and whose downward movement is limited by the first mentioned shoulder at the lower end of the cylinder, the lower end of the mandrel being positioned to operate against said faces to force 15 the blades outwardly upon downward movement of the mandrel.

3. A pipe cutter adapted to cut by rotation and comprising a tubular body whose upper end is formed into a cylinder, outwardly movable blades 20 whose upper ends are pivoted to the body and whose lower ends are swingable outwardly and formed with outwardly directed bits, the blades having downwardly converging, inside faces, means normally holding the blades retracted into 25 inactive position, a mandrel movable axially in the body and extended into the cylinder, said mandrel being tapered at its lower end to engage the converging inside faces of the blades, a shoulder in the lower end of the body, a coil spring 30 resting on the said shoulder, and supporting the mandrel and holding the mandrel normally in inactive position, threads on the upper end of the mandrel adapted to receive a nut for holding said coil spring adjustably in place, a piston in the cylinder above said coil spring, an internal annular shoulder at the lower end of said cylinder for restricting the downward movement of the piston, the upper end of the mandrel being reduced and externally threaded, a nut 35 threaded onto said reduced end of the mandrel for locking the piston in place and a tubular operating string above the piston for the passage of fluid under pressure to operate the mandrel 40 downwardly.

JAMES BUCKLES.
